STEP-ON DUST PAN

Louis J. Sofro, Pawtucket, R. I.

Application February 23, 1956, Serial No. 40,280

Term of patent 7 years

(Cl. D44—18)

Fig. 4

Fig. 1 is a top plan view of a step-on dust pan, showing my new design;

Fig. 2 is a bottom plan view;

Fig. 3 is an edge view thereof; and

Fig. 4 is a perspective view.

I claim:

The ornamental design for a step-on dust pan, as shown.
